P. N. Parmeroy
ATTORNEY

UNITED STATES PATENT OFFICE.

VINCENT LINK, OF DETROIT, MICHIGAN, ASSIGNOR TO THE STUDEBAKER CORPORATION, OF SOUTH BEND, INDIANA, A CORPORATION OF NEW JERSEY.

CONTROL MECHANISM.

Application filed April 14, 1924. Serial No. 706,407.

To all whom it may concern:

Be it known that I, VINCENT LINK, a citizen of the United States of America, and resident of Detroit, in the county of Wayne and State of Michigan, have invented certain new and useful Improvements in Control Mechanism, of which the following is a specification.

This invention relates to levers and the like of the type provided with a latch for holding the lever in a fixed position.

One object of the present invention is to provide such a lever having a simplified and improved latch operating mechanism.

Another object is to provide such a lever in which the conventional pin for pivoting the latch operating handle to the body of the lever is dispensed with.

Another object is to provide such a lever in which the latch operating handle is provided with a projection adapted to be received in an opening in the body of the lever and about which the handle is adapted to pivot.

Still another object is to provide a lever of the type mentioned in which a single resilient means is employed to hold the handle in place on the lever with the latch mechanism in operative position and which will effectually prevent rattling of the latch mechanism carried by the handle.

The above being among the objects of the present invention, the same consists of certain features of construction and combination of parts to be hereinafter described, in reference to the accompanying drawing, and then claimed, having the above and other objects in view.

In the accompanying drawing which illustrates a suitable embodiment of the present invention, and in which like numerals refer to like parts throughout the several views;

Figure 1 is a partially sectioned side view of a brake lever embodying the present invention shown mounted in operative position upon a suitable support.

Figure 2 is an enlarged fragmentary sectional side view of the upper end of the lever of Figure 1 taken through the center of the lever.

Figure 3 is a section taken on the line 3-3 of Figure 1.

Figure 4 is a section of the latch operating handle only, taken on the line 3-3 of Figure 1.

Figure 5 is an enlarged section of the lever handle only, taken on the line 5-5 of Figure 1.

The brake lever consists of a main body portion 10 formed from sheet metal bent into a U shaped section as shown in Figure 3. The lower end is formed into a yoke 11 and is provided with a pin 12 for pivotally connecting it to the rod, 13, which in turn is connected to suitable lever operated mechanism not shown. A triangular pivot member 14 is inserted and secured between the U of the main body portion 10 in the position indicated in Figure 1, leaving one corner of the pivot member projecting outwardly to receive the pin 15 secured to the supporting member 16, the lever as a whole being pivotally supported by the pin 15. The upper end of the main body portion 10 constituting the handle 17 of the lever is formed into a split tubular section, as clearly shown in Figure 5, and a tubular sleeve 18 is pressed thereover as shown in Figures 1 and 5, a portion of the sleeve 18 being allowed to project a slight amount above the portion 17 to receive the finishing button 19 therein.

Secured to the support 16 is a ratchet sector 20, provided with ratchet teeth 21 on its inner surface disposed in a circumferential path about the center of the pin 15, and pivotally secured to the main body portion 10 of the lever at 22 is the pawl or latch 23 normally tending to engage the ratchet teeth 21 by means to be hereinafter described.

Pivotally secured to the upper end of the lever is the latch operating handle 24, preferably formed of sheet metal into a U-shaped section. The lower portion of the handle 24 is provided with two extending ears 25 in the form of a yoke which straddle the body portion 10 of the lever, as clearly shown in Figure 3, and project past the opposite side thereof as shown in Figures 1, 2, and 3. A portion of the metal at the lower end of the handle 25 is bent up to a position substantially perpendicular to the line of the handle 24 to form a projection 26 disposed between the ears 25. This projec-

tion 26 is adapted to be received in an opening 27 formed in the main body portion 10 of the lever at the base of the U as shown in the drawings, and the handle 24 is adapted to pivot about the line of contact between the projection 26 and body portion 10 at the edge of the opening 27. Adjacent the extremity of each of the ears 25 is provided an opening 28 which is adapted to receive 10 the pin 29. A latch rod 30 is pivotally connected by the pin 29 to the ears 25 and extends downwardly and is pivotally connected to the latch 23 as shown in Figure 1. A spring 31 having a foot 32 seated within the 15 U of the main body portion 10 is looped around the pin 29 and has an extending arm 33 which is adapted to rest against the upper face of the projection 26. The end 33 of the spring 31, when free, or in other words 20 when not engaging the projection 26, assumes a position as shown in dotted lines in Figure 2 as 33^a. When, therefore, the end 33 of the spring is sprung up over the projection 26 and engages its upper face it exerts a pressure thereon in the direction of 25 the arrow 34, Figure 2, and causes the foot 32 to exert a pressure against the body portion 10 in the direction of the arrow 35. The reaction to the force indicated by the 30 arrow 34 is, of course, equal and opposite thereto, and is exerted at the pin 29, as indicated by the arrow 36, tending to lift the same and to rotate the handle 24 about the line of contact between the projection 26 and body portion 10 at the edge of the opening 27. This lifts the rod 30 and causes the 35 latch 23 to engage the ratchet teeth 21 on the sector 20, the length of the rod 30 limiting the upward travel of the pin 29 and consequently the amount of rotation of the 40 handle 24. The reaction to the pressure indicated by the arrow 35 exerted by the foot 32 of the spring 31 against the body portion 10 is likewise equal and opposite thereto and is exerted at the pin 29 as indicated by the 45 arrow 37, and tends to pull the lower end of the handle 24 into closer relationship with the body portion 10 of the lever. It is thus evident that the handle 24, rod 30 and latch 50 23 are normally under a spring pressure which effectually holds the parts in position, and prevents inadvertent movement and consequent rattling of the same.

It is further evident that when the latch handle 24 is drawn towards the lever handle 55 17 the latch handle 24 pivots about the line of contact between the projection 26 and body portion 10 at the edge of the opening 27 and causes the pin 29 carried by the ears 60 26 to move downwardly, moving the rod 30 downwardly and releasing the latch 23 from contact with the ratchet teeth 21, thereby allowing the lever to pivot about the center of the pin 15. It is also evident that as soon 65 as the latch operating handle 24 is released

by the operator, the spring 31 will again bring all the parts into normally operating position.

The construction shown will be recognized as being an extremely simple, efficient construction and one that may be economically produced, but I do not limit myself to the specific construction shown and described, as formal changes may be made in the same without departing from the spirit and substance of the broad invention, the scope of which is commensurate with the appended claims.

What I claim is:

1. In combination, a lever provided with 80 an opening therein, a handle provided with a yoke straddling said lever, and a projection seating in said opening for pivotally supporting said handle.

2. In combination, a pivotally mounted 85 lever provided with an opening therein, a handle provided with a tongue adapted to seat in said opening, latch mechanism controlled by said handle, and single resilient means for holding said tongue in said opening and for holding said latch mechanism 90 in operative position.

3. In combination, a lever provided with 95 an opening therein, a handle provided with a yoke straddling said lever, a projection on said handle adapted to be received within said opening, and resilient means to hold said projection within said opening and to cause said handle to pivot about said opening.

4. In combination, a lever provided with 100 an opening therein, a latch carried by said lever, a handle provided with an extending part engaging said opening which said handle is adapted to pivot about, a rod connecting said handle and said latch, and single spring means for holding said handle in position on said lever and for causing said latch to normally assume operative position.

5. The combination with a lever having 110 an opening therein, of a handle provided with a projection adapted to enter said opening, ears on said handle forming a yoke straddling said lever, a pin supported at the extremities of said ears, and a spring 115 looped around said pin, one end of said spring seating against said projection and the other end seating against said lever.

6. In combination, a lever provided with 120 an opening, a handle provided with a yoke straddling said lever, a projection on said handle disposed within said yoke and projecting through said opening, a pin carried by the free ends of said yoke, and a spring 125 looped around said pin, said spring being provided with an arm normally pressing down on said projection and with another arm normally pressing against said lever.

7. In combination, a support, a lever pivotally mounted on said support, a ratchet

- sector mounted on said support, a pawl pivoted to said lever adapted to engage said ratchet sector, an opening in said lever adjacent its upper end, a handle provided with 5 a yoke straddling said lever and with a projection engaging said opening, a pin carried adjacent the extremities of said yoke, a rod connecting said pin and said pawl, and a spring supported by said handle provided with an arm pressing down on said projection and with another arm pressing against said lever below said opening.

Signed by me at Detroit, Michigan, U. S. A., this 8th day of April, 1924.

VINCENT LINK.
